REFRACTORY ELEMENT FOR STOVES
AND THE LIKEJohn C. Miles, Urbana, Ill., assignor to The Board
of Trustees, the University of Illinois

Application April 8, 1946, Serial No. 660,495

1 Claim. (Cl. 126—146)

1

This invention relates to a hot water heater or the like.

The hot water heater which is the subject of this invention is especially designed for supplying hot water in installations where relatively small amounts of water are required. It is of very simple construction, and is quite cheap to build. The apparatus has all heated parts water-jacketed, so that it may be made of metal. Although preferably used as a water heater, the structure may also be used as a boiler.

Previous water heaters using coal as the power have been bulky, expensive, and required insulation with firebrick or the like to protect the sides from the heat of the fire. The present construction is much superior to these previous water heaters in that it is light in weight, inexpensive to construct, and is highly efficient in furnishing a constant supply of hot water.

The invention will be described as related to the accompanying drawings, which illustrate one embodiment of the hot water heater. Of the drawings, Fig. 1 is a vertical sectional elevation taken substantially through the center of the heater; Fig. 2 is a section taken along line 2—2 of Fig. 1; Fig. 3 is a section taken along line 3—3 of Fig. 1; and Fig. 4 is a perspective view of one section of the secondary air intake thimble.

The hot water heater shown in the accompanying drawings comprises firebox 10 of substantially circular cross-section containing a coking zone 11, a coke-burning zone 12, and a combustion zone 13. Communicating with the combustion zone is passageway 14 serving as an outlet for the gases of combustion. This passageway is connected at the top with a stack 15. The firebox 10 and passageway 14 are made of metal, and are water-jacketed by means of partitions 16 and 17. The water jacket 18 around the firebox is connected to water jacket 19 around the combustion gas passageway, as with a short U-shaped pipe 20. Water is permitted to flow into the firebox jacket 18 through said pipe 21, located near the bottom of the heater and up around the firebox and the passageway 14, and out the exit pipe 22. In this travel the water is heated by the fire in the firebox, and the heated gases of combustion in the passageway 14.

The bottom of the hot water heater contains an ash pit 23, separated from the firebox by an inclined fixed grate 24 and a flat shaker grate 25. The ash pit has an ash removal door 26, in which is located a small air hole 27.

At the top of the firebox there is located a refractory thimble 28, of triangular cross-section,

having one side curved to fit against the side of the firebox. The thimble has a hollow interior 29, which forms a part of the combustion zone of the heater. The thimble 28 also has a channeled exterior 30 communicating with the atmosphere through a hole in the side of the firebox. This air hole is formed by means of a short pipe 31 passing through the water jacket. The channel 30 in the refractory thimble is closed at its curved side by the metal wall of the water heater, and is partially closed at its other two sides by means of refractory elements 32. These refractory elements are cut away at the bottom to form an air inlet 33 at the bottom of the thimble. This air inlet supplies air to the combustion zone of the hot water heater. Thus air flows through the short pipe 31 around the thimble channel 30 and out the air inlet 33 at the bottom of the thimble. The air thus admitted mixes with the combustible gases and passes up through the hollow interior of the thimble where the gases are burned in the combustion zone.

The refractory elements 32 which serve to partially close the two sides of the channel on the outside of the thimble are held in place by means of a top metal member 34 fixed to the top of the heater, and by means of side metal members 35 contacting the sides of the firebox but spaced therefrom. These side metal members 35 press against the refractory elements and help hold them in place against the thimble 28. The side members contain a plurality of spaced holes 36, and there are holes 37 at the bottom of the firebox but within the space between the side members and the sides of the firebox. These holes are in communication with the under-grate air supply that enters the heater through air hole 27 in the ash removal door 26.

The refractory thimble 28 is divided into two equal and opposite sections 28a (Fig. 4) by a plane of division passing through the apex of the thimble. Such a construction makes it easy to insert and remove the thimble.

It is preferred that the refractory thimble 28 be positioned at the top of the firebox so that the space between the bottom of the thimble and the bottom of the firebox is considerably greater than the space between the bottom of the thimble and the top of the firebox. This provides a slow burning rate as the depth of coke is large in relation to the depth of uncoked coal. The top of the coke will be substantially even with the bottom of the refractory thimble. In a typical heater there is approximately as much coke as there is uncoked coal.

When the hot water heater is in operation primary air is supplied through air hole 27 in the ash removal door 25. A portion of this primary air passes up through the grates to serve as primary under-grate air, while another portion flows through air holes 37 in the bottom of the firebox up between the sides of the firebox and side metal members 35, and out through holes 36 in these side members to the coking zone. Secondary combustion air is supplied through secondary air pipe 31, where it flows around the channel 30 in the refractory thimble 28 and out the bottom of the thimble into the combustion zone 13.

The inclined fixed grate 24 is provided with slots 38 through which the ashes fall. This inclined grate also provides for passage of air and directs the coke toward the rear. These slots are arranged in parallel alignment, and extend from near the side of the firebox through the other edge of the fixed grate. As the fixed grate is made of metal and contacts the metal side of the firebox, this construction permits the inclined grate to expand and contract without exerting any force on the metal sides of the firebox. As the side of the firebox is water-jacketed, it will not expand and contract under heat. The parallel slots 38 are wider at the bottom than they are at the top, in order to permit ashes to drop through freely. The slots may be $\frac{1}{8}$ " wide at the top and $\frac{1}{4}$ " wide at the bottom.

The hot water heater as shown is provided with a feed opening 39 at the top of the firebox. If the feed opening is made small, smoke will not leak out when it is open. In one construction where the firebox had an internal diameter of $15\frac{3}{4}$ " diameter, the feed door was $4\frac{1}{4}$ " at its smallest diameter. This same hot water heater had the firebox 16" high with the bottom of the refractory thimble 9" from the bottom of the firebox.

It was found that for best construction, a hot water heater of this type should be of circular cross-section, in order to equalize stresses in the metal sides. These stresses are caused by the pressure of water flowing through the water jackets, and by the heat stresses from the burning coal.

For very cheap construction and low water demand, the top passageway 14 could be left off, with the stack connected directly to the firebox. In those preferred installations where the top passageway is used, this passageway may be permitted to merely rest on top of the firebox and be held there by its own weight. It is preferred,

however, that some means of fastening the two together be used.

Having described my invention in relation to a typical embodiment of same, it is to be understood that the invention is not to be limited to any of the details of description unless otherwise specified, but rather be construed broadly within its spirit and scope as set out in the accompanying claim.

10 I claim:

A longitudinally split refractory element for use in a stove and the like wherein said stove is provided with an air supply opening to the interior thereof and an exit for burned gases at the top of the stove, said refractory element comprising a hollow body portion open at top and bottom serving as a combustion chamber when the body portion is arranged in communication at the bottom with said interior of the stove and at the top with said exit for burned gases, and said body portion having a transverse outwardly extending flange at each of the top and bottom ends thereof with the space defined by said flanges and the outer surface of said body portion serving as an air channel when said space is arranged in communication with said air supply opening and with the bottom of said combustion chamber, said body portion being of substantially triangular transverse cross-section with one side being curved convexly and the other two sides being substantially straight and of substantially the same area, and with the split being formed by a plane lying substantially along the apex of the angle formed by the two straight sides and bisecting the curved side into two substantially equal parts.

JOHN C. MILES.
